His Attorney.

UNITED STATES PATENT OFFICE.

EDWARD W. KELLOGG, OF SCHENECTADY, NEW YORK, ASSIGNOR TO GENERAL ELECTRIC COMPANY, A CORPORATION OF NEW YORK.

SOUND-REPRODUCING APPARATUS.

Application filed January 9, 1925, Serial No. 1,483. Renewed May 18, 1927.

My present invention relates to apparatus for producing sound from electric currents corresponding to original sounds, and more particularly to devices now commonly known 5 as loud speakers.

One of the objects of my invention is to provide a device of the class mentioned whereby the reproduction of sounds may be made with greater accuracy and fidelity than 10 with devices of this class previously employed.

A further object of my invention is to provide an apparatus in which the usual horn may be dispensed with and the sound projected from the device in a more satisfactory 15 manner than with the usual form of horn.

The novel features which I believe to be characteristic of my invention are set forth with particularity in the appended claims. 20 My invention itself, however, both as to its organization and method of operation will best be understood by reference to the following description taken in connection with the accompanying drawing in which Fig. 1 is a 25 view partly in cross-section of a device constructed in accordance with my invention; Fig. 2 is an enlarged cross-section detail showing the method of supporting the outer edge of the diaphragm; Fig. 3 is an enlarged 30 cross-sectional detail showing the manner in which the actuating means is supplied to the diaphragm, and Fig. 4 is a perspective exploded view of the arrangement shown in Fig. 3.

I have indicated in the drawing a sound 35 reproducing device comprising a diaphragm 1 of conical form which, in the device illustrated, is specifically a truncated cone. The outer edge or base of the diaphragm is secured to a supporting ring 2 by means of a ring 3 of flexible material such as silk, rubber, or thin leather. The diaphragm 1 may be made of paper or other light material whereby the diaphragm will be made rigid 40 enough so that it will be capable of vibrating substantially as a whole. The top or inner edge of the diaphragm is made in the form of a cylinder 4 which is provided with inner and outer reinforcing rings 5 and 6. The 45 actuating means for the diaphragm comprises a coil 7, surrounding the inner reinforcing ring 5, and secured thereto in any suitable manner. The coil 7 is disposed in the annular air gap 8 which is formed be-

tween the concentric pole pieces 9 and 10. 55 The inner pole piece 9 is surrounded by a coil 11 through which a steady direct current may be supplied for producing a strong magnetic field in the annular air gap 8.

When variable currents are supplied to 60 the coil 7 the diaphragm 1 will be caused to vibrate substantially as a whole in accordance with the variations in current supplied to the coil. Because of the flexible nature of the ring 3 there may be a tendency for lateral movement of the coil 7 in the air gap 8. To avoid this the inner pole piece 9 is provided at its center with a projection 10 and a spider 11 is secured to this extension by means of the screw 12. This spider is provided with a plurality of resilient arms 13 70 extending in directions substantially parallel to the axis of the pole piece 9. These arms 13 are all connected by radially extending connecting links 14 with the top of the diaphragm. These connections are located in a plane substantially parallel with the base of the diaphragm and may be made part of a continuous length of cord or fine wire threaded through holes in the ends of the arms 13 80 and through the end of the diaphragm, as indicated. When these connections are made taut they will substantially prevent all lateral movement of the coil 7, and at the same time will not interfere to any appreciable 85 extent with longitudinal movement of the coil in air gap 8.

One feature which is essential to the satisfactory operation of a loud speaker is the avoidance of resonant air chambers next to 90 the diaphragm. For example, if the space behind the diaphragm is completely enclosed there will be a certain frequency at which the enclosed air will furnish an elastic restoring force to the diaphragm causing a strong resonance effect and other frequencies at which the air will so resist motion of the diaphragm as to greatly reduce its amplitude of vibration. To eliminate any enclosed air space between the diaphragm and the pole pieces 95 of the polarizing magnet the top of the cone is left open. The clearance between the top of the cone and the pole pieces may be made small enough so that in spite of the open end construction there will be no great loss 100 due to leakage around the inner edge of the diaphragm.

The supporting ring 2 may be mounted on

the pole piece 10 by means of brackets 15. The magnetic structure may be secured by suitable brackets 16 to any desired form of support 17. The restoring force of the diaphragm mounted in the way illustrated may be made so low that its natural rate of vibration as a whole will be below the lowest important voice frequency. For example, I have constructed paper diaphragms of the form indicated of a diameter of five and $\frac{3}{4}$ inches and have found that when mounted in the manner described these diaphragms have a natural rate of vibration as a whole of about 50 cycles. Fairly good results may be obtained however with diaphragms having higher natural frequencies of vibration, even up to 200 cycles, particularly if provision is made for damping so that the resonance is not sharp. This low natural frequency is an essential feature in the construction of loud speakers in order that the diaphragm shall respond equally to all frequencies which it is desired to reproduce.

Both sides of the diaphragm 1 are exposed to the air. As a result no resonant effects will be introduced by reason of confined air. With the arrangement thus far described the air could circulate between the front and back of the diaphragm around the supporting ring 2 without undergoing any appreciable compression. This would result in substantial loss of the low tones. If, however, the path between the front and back of the diaphragm is lengthened to a distance of about a quarter wave length or more, this circulation will be prevented and good radiation may be secured. This effect may be had by surrounding the diaphragm by a baffle 18 of fairly massive or rigid material in such a manner as to effectively prevent circulation. The baffle effect may conveniently be obtained by enclosing the diaphragm and its actuating mechanism in a cabinet of suitable form, which cabinet is provided with an opening in which the supporting ring 2 is fitted. Preferably the back of this cabinet should be open to prevent any resonant effects due to confined air.

The type of loud speaker which I have described and illustrated requires for its operation a comparatively strong magnetic field, and this necessitates supplying to the exciting coils 11 a current of considerable strength. In some cases it may be desirable to produce the field by means of rectified alternating current. Unless an expensive filter system is provided the rectified current will normally be a pulsating current but the magnetic field in the air gap must be practically constant in order to avoid modulation of the tones produced by the loud speaker and the production of tones which are harmonics of the frequency supplied by the rectifier. This difficulty may be avoided by making the end 19 of the field coil spool con-

stitute a short circuited turn of very low resistance, for example, by making it of a heavy ring of copper.

While it may be shown theoretically that a small diaphragm, of such rigid construction that all parts have equal motion even at the highest frequencies, and so supported that its natural frequency of vibration as a whole is below the lowest frequency to be radiated, constitutes an ideal sound reproducer, as explained in my copending application Serial No. 702,455, filed March 27, 1924, I have not found it necessary in practice to adhere to diaphragms of such small size as would be needed to comply with the condition just mentioned. For example, I have made a calculation which indicates that a paper cone, four inches in diameter at the base, free at the outer edges, and with an angle of 45° between axis and element will probably begin to depart materially from true plunger action at a frequency between 3000 and 4000 vibrations per second. Cones with larger diameters or with larger angles between element and axis will begin to show appreciable phase and amplitude differences between the different parts of their surfaces at lower frequencies. I have nevertheless obtained good results with cones up to 8 and even 20 inches in diameter and with angles as great as 64° , provided that in all cases the outer edges of the cone is so flexibly supported that at low frequencies the cone moves as a whole. The probable explanation of this experience is that at the higher frequencies the diaphragm radiates sound by virtue of a progressive deflection. When a force is applied at the small end of the frustum, a circular flexural wave travels out toward the outer edge, and gives off sound waves in the air as it progresses. The progressive deflection I shall refer to as "wave action" in the diaphragm while the type of motion in which all parts of the surface have the same motion may be described as piston or "plunger action". In the devices built in accordance with my invention, true plunger action takes place at the lower frequencies and wave action presumably takes place at the higher frequencies. The transaction is not abrupt, nor is it marked by any great change in radiation characteristics or efficiency which would upset the balance between the high and low frequency components or impair the general quality of sound reproduction. Within the frequency range characterized by wave action in the diaphragm slight resonance may occur, for the reason that reflection of the waves takes place at the outer edge of the diaphragm. The fact that resonances do not appear to be so sharp or strong as to impair sound reproduction is probably due to the high attenuation of the waves at high frequency by energy absorption in the material of the diaphragm, and also in part to energy absorption in the

flexible ring by which the outer edge of the diaphragm is supported.

As compared with diaphragms so small that one can be sure that they act as plungers throughout the entire essential frequency range, I find a gain in sensitivity from the use of somewhat larger sizes, my best results having been obtained with diameters between four and eight inches and angles between element and axis, from 45° to 70°. Diaphragms of large diameter work best with the larger angles. In the case of sound reproducing devices employing conical diaphragms, either rigidly supported at the outer edge, or with a support whose stiffness in the axial direction is comparable with the stiffness of the diaphragm itself, plunger action cannot take place at any frequency. If a vibratory force is applied at or near the vertex the resulting motion is greatest where the force is applied and becomes less as the edge is approached if the frequency is below the fundamental resonances. As the frequency is raised a series of resonances occur. At certain frequencies the motion is greatest at the point of application of the driving force, and at other frequencies the motion is greatest at points between the vertex and the outer edge. Flexural waves originating at the driving point, travel to the outer edge where they are reflected and produce standing waves with circular nodes and loops of motion. At low frequencies the resonances are far apart on the musical scale, and owing to the small absorption of energy, resonance is sharp. Both of these facts mean serious distortion in the reproduction of sounds. At higher frequencies the resonances are closer together on the musical scale and are less sharp because of greater relative energy absorption in the material of the diaphragm and sound radiation is therefore more nearly uniform. With a diaphragm stiffly supported at the edge, there is little motion and little sound radiation at frequencies below the first resonance. Therefore to secure anywhere near adequate radiation of low tones it is necessary to make the diameter large and the angle between element and axis large (giving a shallow cone). My tests indicate however that cones which are very shallow in comparison with their diameters, fail to give adequate radiation of the very high frequency tones.

A device, employing a flexibly supported conical diaphragm, has the following advantages over previous devices having rigid or stiff support around the outer edge. The radiation of the low tones is much more nearly uniform and free from resonance, and the radiation of high frequencies is more satisfactory for the reason that we have more latitude in the choice of cone angle and can choose that which gives the most nearly uniform radiation of the high frequencies. Devices with stiffly supported outer edges must

employ an angle which is a compromise between what is best for the high and low frequencies and is therefore not the best angle for either one. My device has the further advantage that with plunger diaphragm action adequate radiation of low tones can be obtained with a smaller diaphragm, provided that a baffle is used in connection with the diaphragm. This means that the diaphragm is easier to protect from injury and the resulting device becomes more compact.

In the claims which follow I use such expressions as "adapted to vibrate substantially as a whole" and "all parts thereof will have substantially equal movement" to distinguish over diaphragms which are rigidly supported and therefore incapable of vibration as a whole at any frequency, and to include diaphragms such as described which may have a slight wave action at the higher frequencies but in which such action is not detrimental.

Certain features disclosed herein but not claimed are disclosed and claimed in my co-pending application Serial No. 702,455, filed March 27, 1924. Certain other features also disclosed herein but not claimed are disclosed and claimed in the joint application of Chester W. Rice and Edward W. Kellogg, Serial No. 1438, filed January 9, 1925.

What I claim as new and desire to secure by Letters Patent of the United States, is:—

1. In an apparatus for sound reproduction, a diaphragm having the form of a truncated cone which is open at its top and which is so supported that it is adapted to vibrate substantially as a whole, and means for actuating said diaphragm comprising a coil surrounding the top thereof.

2. In an apparatus for sound reproduction, a diaphragm having the form of a truncated cone which is open at its top, and which is so supported that it is adapted to vibrate substantially as a whole, reinforcing means for the top thereof, and means for actuating said diaphragm comprising a coil secured to said reinforcing means.

3. In an apparatus for sound reproduction, a diaphragm having the form of a truncated cone which is open at the top and which is so rigid in comparison with its size and weight that when a driving force is applied thereto at its top all parts thereof will have substantially equal movement, means for suspending said diaphragm having so low a restoring force that its natural rate of vibration as a whole will be below the lowest important voice frequency, and means for actuating said diaphragm comprising a coil surrounding the top thereof.

4. In an apparatus for sound reproduction, a diaphragm having the form of a truncated cone which is open at its top and which is so rigid in comparison with its size and weight that when a driving force is applied thereto at its top all parts thereof will have substan-

- tially equal movement, means for suspending said diaphragm having so low a restoring force that its natural rate of vibration as a whole will be below the lowest important 5 voice frequency, reinforcing means for the top of said diaphragm, and means for actuating said diaphragm comprising a coil secured to said reinforcing means.
6. In an apparatus for sound reproduction, 10 a diaphragm having the form of a truncated cone which is open at its top and which is so rigid in comparison with its size and weight that when a driving force is applied thereto at its top all parts thereof will have substantially equal movement, means for suspending said diaphragm having so low a restoring force that its natural rate of vibration as a whole will be below the lowest important voice 15 frequency, means for actuating said diaphragm comprising a pair of concentric pole pieces separated by an annular air gap, and an actuating coil secured to the top of said diaphragm and located in said air gap.
7. In an apparatus for sound reproduction, 20 a rigid diaphragm having the form of a truncated cone which is open at the top, the base of said diaphragm being so flexibly supported that the diaphragm is adapted to vibrate substantially as a whole, means for actuating said diaphragm comprising a pair of concentric pole pieces separated by an annular air gap and an actuating coil secured to the top of said diaphragm and located in said air gap.
8. In an apparatus for sound reproduction, 25 a diaphragm having the form of a truncated cone which is open at its top and which is so supported that it is adapted to vibrate substantially as a whole, and means for actuating said diaphragm comprising a coil surrounding the top thereof, said diaphragm being so arranged that air can circulate freely on both sides thereof, and a baffle surrounding said diaphragm for increasing the length of the 30 path through the air between the two sides of the diaphragm.
9. In an apparatus for sound reproduction, 35 a rigid diaphragm having the form of a truncated cone, the base of said diaphragm being so flexibly supported that the diaphragm is adapted to vibrate as a whole, means for actuating said diaphragm comprising a pair of concentric pole pieces separated by an annular air gap, an actuating coil secured to the top of said diaphragm and located in said air gap, and means secured to the inner of said pole pieces for preventing lateral movement of said coil in said air gap.
10. In an apparatus for sound reproduction, 40 a rigid diaphragm having the form of a truncated cone, the base of said diaphragm being so flexibly supported that the diaphragm is adapted to vibrate as a whole, means for actuating said diaphragm comprising a pair of concentric pole pieces separated by an annular air gap, an actuating coil secured to the top of said diaphragm and located in said air gap, and means for preventing lateral movement of said coil in said air gap, comprising a spider secured to the inner of said pole pieces, said spider having a plurality of flexible arms, and each of said arms being connected by radially extending connections to the top of said diaphragm. 45
11. In an apparatus for sound reproduction, a rigid diaphragm having the form of a truncated cone, the base of said diaphragm being so flexibly supported that the diaphragm is adapted to vibrate as a whole, means for actuating said diaphragm comprising a pair of concentric pole pieces separated by an annular air gap, an actuating coil secured to the top of said diaphragm and located in said air gap, and means for preventing lateral movement of said coil in said air gap comprising a spider secured to the inner of said pole pieces, said spider having a plurality of flexible arms, and each of said arms being connected by radially extending connections to the top of said diaphragm, said connections being taut in the direction of lateral movement of said coil but flexible in the direction of longitudinal movement thereof. 50
12. In an apparatus for sound reproduction, a rigid diaphragm having the form of a truncated cone which is open at its top, the base of said diaphragm being so flexibly supported that the diaphragm is adapted to vibrate as a whole, means for actuating said diaphragm comprising a pair of concentric pole pieces separated by an annular air gap, an actuating coil secured to the top of said diaphragm and located in said air gap, and means for preventing lateral movement of said coil in said air gap comprising a spider secured to the inner of said pole pieces, said spider having a plurality of flexible arms extending in directions substantially parallel to the longitudinal axis of said diaphragm, and each of said arms being connected by radially extending connections to the top of said diaphragm. 55
13. In an apparatus for sound reproduction, a rigid diaphragm having the form of a truncated cone which is open at its top, the base of said diaphragm being so flexibly supported that the diaphragm is adapted to vibrate as a whole, means for actuating said diaphragm comprising a pair of concentric pole pieces separated by an annular air gap, an actuating coil secured to the top of said diaphragm and located in said air gap, and means secured to the inner of said pole pieces for preventing lateral movement of said coil in said air gap. 60
14. In an apparatus for sound reproduction, a rigid diaphragm having the form of a truncated cone open at the top and a plu- 65

rality of supporting means for said diaphragm located in substantially parallel planes near the base and top thereof, said supporting means being so flexible as to permit vibration of the diaphragm substantially as a whole.

14. In an apparatus for sound reproduction, a rigid diaphragm having the form of a truncated cone which is open at its top, the base of said diaphragm being so flexibly supported that the diaphragm is adapted to vibrate as a whole, means for actuating said diaphragm comprising a pair of concentric pole pieces separated by an annular air gap, an actuating coil secured to the top of said diaphragm and located in said air gap, and flexible supporting means for said diaphragm located in a plane substantially parallel with the base of said diaphragm and secured to the inner of said pole pieces.

15. In an apparatus for sound reproduction,

25 a diaphragm having the form of a truncated cone which is so rigid in comparison with its size and weight that when a driving force is applied thereto at its top all parts thereof will have substantially equal movement, means for suspending said diaphragm having so low a restoring force that its natural rate of vibration as a whole will be below the lowest important voice frequency, 30 means for actuating said diaphragm comprising a pair of concentric pole pieces separated by an annular air gap, an actuating coil secured to the top of said diaphragm and located in said air gap, and means secured 35 to the inner of said pole pieces for preventing lateral movement of said coil in said air gap.

In witness whereof, I have hereunto set my hand this 8th day of January, 1925.

EDWARD W. KELLOGG.
